DESIGN FOR A KITCHEN SPOON OR SIMILAR ARTICLE

Walter O. Brown, Detroit, Mich.

Application October 23, 1944, Serial No. 115,932

Term of patent 14 years

(Cl. D54—12)

To all whom it may concern:

Be it known that I, Walter O. Brown, a subject of the King of Great Britain, residing at Detroit, in the county of Wayne and State of Michigan, have invented a new, original, and ornamental Design for a Kitchen Spoon or Similar Article, of which the following is a specification, reference being had to the accompanying drawing, forming part thereof in which—

Fig. 1 is a side elevation of a kitchen spoon or similar article showing the essential features of my design in full lines. Fig. 2 is a fragmentary view of the opposite side of the spoon shown in Fig. 1. Fig. 3 is a fragmentary top plan view thereof.

I claim:

The ornamental design for a kitchen spoon or similar article, substantially as shown and described.

WALTER O. BROWN.
